UNITED STATES PATENT OFFICE.

JOHANN SCHEUNER, OF KONOLFINGEN, SWITZERLAND.

APPARATUS FOR FEEDING FOLDED MATTER INTO PRINTING MACHINES.

Application filed April 16, 1923. Serial No. 632,184.

To all whom it may concern:

Be it known that I, JOHANN SCHEUNER, a citizen of the Swiss Confederation, and residing at Konolfingen, Switzerland, have invented a certain new and useful Apparatus for Feeding Folded Matter into Printing Machines.

My invention relates to apparatus for feeding folded matter into printing machines.

Apparatus used heretofore for feeding unfolded paper into printing machines cannot be used for feeding folded paper, such as folded newspapers, pamphlets and the like, into printing machines having continuous type, for example addressing machines having lines of type fed intermittently from a type-setting machine, because folded papers when laid in a pile are higher at the fold side than at the open side, so that a pile of folded papers is uneven. Also, the thickness of a folded paper varies according to the number of times it is folded. Further, folded papers are looser or spaced further apart than when unfolded and their looseness or spacing varies with the thickness of the paper.

This invention has for its object to provide an apparatus for feeding folded matter in printing machines, which apparatus shall take account of all these properties of folded paper without requiring adjustment of one of its constituent members, and which shall be serviceable.

This end I attain, in one form of apparatus according to the invention, by providing points that are movable in their longitudinal direction and transversely thereof, which points when driven into a piece of folded material remove the same from a pile-holder in order that it may then be conveyed by transport members that cooperate with the points. The points are driven, e. g., snapped, into the folded piece of material to be fed into the machine, so that they penetrate a greater or smaller number of layers according to the thickness of the folded paper, and consequently the points seize the folded papers always equally firmly no matter how thick and stout they may be, and of whatever structure the paper is, whether supple or bulky, smooth or rough.

The points aforesaid are preferably mounted on levers that extend transversely of the points above the same, which levers

are reciprocated endwise transversely of the longitudinal direction of a plate or track carrying a pile of the folded pieces, and are controlled by a controllable guide by which the point-carrying levers can be moved rectilinearly for stopping their feed motion, or in a circle for the purpose of feeding, the levers being snapped under the action of a spring against the piece of paper to be fed, for the purpose of driving the said points into the latter.

The plate or track for carrying the pile of folded pieces is conveniently laid slantwise in relation to the point-carrying levers which move up and down, so that folded pieces placed upright on the track will automatically slide towards the said levers and successively pass within reach of the same.

The said track may be arranged above a table with one end connected to it, and the pile-holder may be formed by a stop that tapers upwards at its upper end which is directed towards the track, by which stop a folded piece that is lifted over it by the point-carrying levers is brought, when falling, into a slanting position in relation to the table.

The invention consists in the construction, arrangement and combination of parts hereinafter described and more specifically pointed out in the claims.

One embodiment of my invention is illustrated by way of example in the accompanying drawings, wherein:—

Figure 1 is a longitudinal section of the apparatus as applied to an addressing machine,

Figure 2 is a plan of the same,

Figure 3 is a transverse vertical section taken on the line III—III in Figure 1, and

Figures 4 and 5 are details drawn to a larger scale.

Like reference numerals designate like parts throughout the several views.

A table 1 supported by feet, not shown, has at one end two brackets 2 which support above the table a plate 3 mounted to swing about horizontal pivots 4 at its end adjacent the table. This plate is adjustable into various slanting positions by means of toothed racks 5 provided on it and long pawls 6 pivoted to the brackets 2, and serves to support a pile of folded material 7, e. g., folded paper, placed edgewise nearly upright on it as shown in Fig. 1. In order that the paper

shall automatically slide downwards, i. e., towards the lower end of the plate 3 there is placed, at the back of the pile a rest 8 that runs on wheels, which rest under the action 5 of gravity presses against the pile 7 and holds the papers nearly upright and gently pressed together.

At the lower end of the plate 3 is provided an upwardly tapered pile-holder 9 10 which limits the movement of the pile in a downward direction and slants towards the upper end of the plate 3. This holder 9 has a depending tail piece 10 to which is attached one end of a spring 12 wound round 15 the pivot pin 11 of the pile-holder, by which spring the holder is pressed against the front folded paper of the pile 7.

This front paper can be pulled upwards by two levers 13 which are provided at their 20 lower ends each with a point 14, and are moved up and down. These levers 13 are double ended and are fulcrumed each on an arm 16 secured to a horizontal rock shaft 15. A spring 17 engaging the upper end of each 25 lever 13 tends to hold the same in the position shown in full lines in Figure 1, in which the lower ends contact with the front piece of paper of the pile 7.

The points 14 are located transversely of 30 the longitudinal axis of the axle 18 of the levers 13, and in order that these points shall be held out of contact with the front piece of paper should any disturbances occur in the operation of the addressing machine to 35 which the paper is fed and whenever the levers 13 move downwards during the operation of the machine, each lever 13 is provided with an adjustable guiding device which will now be described.

40 The two levers 13 are provided each with an arm 19 having at its free end a laterally directed pin 20. These pins extend each into a box 21 constituting a cam having in its upper portion a wall 22 rising in a direction away from the corresponding lever 13, and having connected to that portion an extension 23 directed vertically upwards. On the one end wall there is arranged inside the box a guide 24 having a straight face for 45 guiding the pin 20 in line with the wall 23, a passage 25 being left for the pin between the top of the guide 24 and the wall 22, and another passage 26 being provided below. The passage 25 is normally closed by means of 50 a spring-pressed tongue 27 that bears against the upper end of the wall 22. This tongue allows the pin 20 to pass in only one direction, namely when moving upwards along the wall 22. When moving downwards the 55 pin is prevented by the tongue 27 from entering into the passage 25 on reaching the lower end of the wall 23. The passage 26 is controlled by a switch 29 slidable to and fro on the bottom of the box, and having on the 60 one side a slanting, and on the other side,

i. e., that nearer the corresponding lever 13, a vertical face. A pin 30 extending to one side of the switch 29 extends through a horizontal slot 31 of the end wall of the box and is pulled by a spring 32 towards the corresponding lever 13. This spring causes the switch 29 to close the passage 26, as indicated in dotted lines in Figure 4. When the switch is in this position and the lever 13 moves downwards, the pin 20 cannot enter the passage 26, so that the lever cannot rock towards the front piece of paper in the pile 7 and therefore its point 14 cannot enter the same, as indicated by the dash-and-dot lines in Figure 1.

If, on the contrary, the switch 29 is pressed back into the position shown in full lines in Figure 4 by a finger 33 acting on the pin 30 against the action of the spring 32, then the passage 26 is open and the pin 20 can pass out of the vertical guide channel 34 below the guide 24 and through into the broader upwardly directed channel 35. As soon as the pins slide down off the guide 24, the springs 17 operate and rock the levers 13 towards the rear, whereby the points 14 snap into the front piece of paper in the pile 7. Because of their rapid movement, the pins 14 enter through one or more layers of paper depending on its thickness. When the levers 13 are moved upwards immediately afterwards by the arms 16, the front piece of paper into which the points 14 have entered is pulled upwards until the levers 13 begin to swing forwards which occurs when the pins 20 abut from below against the slanting walls 22. During the further upward movement of the levers 13 the pins slide up along the walls 22, press the tongues 27 back and pass into the channel 34. During the subsequent downward movement of the levers 13 the tongues 27 guide the pins 20 into the lower part of the channel 34. Consequently, during this downward movement of the levers 13, the pins 14 remain 100 out of contact with the lifted piece of paper and the next one in the pile.

Owing to the vertical arrangement of the pieces of paper on the plate 3, there is no danger of the piece next but one to the front being moved by friction by the front piece when this is lifted. For successively lifting the pieces of paper, the pins 14 thus move along a somewhat circular path and make in succession a movement in their longitudinal direction (towards the rear), then a movement transverse thereof (upwards), then another movement in the longitudinal direction (but in the opposite direction) 110 and finally another movement in the transverse direction (downwards).

In order to prevent the lifted piece of paper from sliding down immediately after the points 14 are withdrawn from it, there is mounted on a lever 36, which can rock 115

about a pivot 37, a roller 38 which bearing against the lifted piece of paper, presses it against the upper edge of the front end of the pile 7 until the lever 36 is lifted, by means of a loop 39 pivoted to its free end, by a lever 41 that has a pin 40 extending laterally into the loop. The lever 41 is fast on the shaft 15 which is oscillated by a lever 42 and a link 43 by a lever (not shown) under the table 1.

Above the level of the table top 1 are situated the slanting upper lengths of two endless conveyer belts 44 arranged approximately parallel with the longitudinal direction of the plate 3. These belts run on pulleys 45, 46, 47 and serve to convey the paper that is released by the roller 38, and slides downwards, into the reach of feed hooks 48 that reciprocate parallel with the belts 44. These hooks are fast on a shaft 49 journaled in two levers or pendulums 51 swinging about a shaft 50. The levers 51 are adjustably mounted on the shaft 50 which is oscillated by a lever 52 and a link 54 adjustably connected with the latter by an adjustable slide 53 having a set screw, which link 54 can be actuated in any convenient manner, for example by a lever, not shown, under the table 1.

The shafts 15 and 50 as well as a cross bar 57 that carries the boxes or cams 21 by means of arms 55 and adjustable forks 56 are journaled at their ends in two standards 58 provided on the table 1. By shifting the slide 53 and thereby changing the point of connection of the link 54 with the lever 52 the amount of oscillation of the levers 51 can be varied and adapted to the breadth of the piece of paper to be fed.

Fast on the shaft 49 is an arm 59 that bears by means of an anti-friction roller 60 on the free end of a rod 61 which at the other end, is pivoted to rock on the guide 62 of the printing plate 63 of the addressing machine and bears on a cam 64. This cam is fast on the shaft 65 carrying a lever 66 which is connected by a link 67 with a lever 69 mounted to rock about a shaft 68. The lever 69 is connected by a connecting rod 70 with a lever 72 that is under the action of a spring 71 tending to pull it to the rear or to the right in Figure 1. The shaft 73 of lever 72 carries the above-said fingers 33 that control the above said switches 29.

An arm 74 on the lever 69 carries at its free end an anti-friction roller 75, on which bears the free end of an arm 77 rotatable about a horizontal axle 76. This axle also carries an arm 78 which extends under a bowed member 79 for the pieces of paper on which the address has been printed.

If the lever 69 is rocked out of the position indicated in full lines in Figure 1 into that shown in dotted lines, the cam 64 is raised, the lever 72 pulled forwards and the

arms 77 and 78 are lifted. The cam 64 also lifts the rod 61 which moves the arm 59 and the feed hooks 48 upwards, so that the latter can no longer engage and feed a piece of paper lying on the table and on the belts 44. The fingers 33 are moved by the lever 72 out of reach of the pins 30, so that the springs 32 can shift the switches 29 into their closing position in which the pins 20 are prevented by them from passing out of the channel 34, and consequently the levers 13 cannot move into the position for seizing the bottom piece of the pile 7. The lifting of the arms 77 and 78 causes the member 79 to slide to and fro over the piece of paper in the position for printing, without engaging it. Consequently, in the position of the lever 69 indicated by the dotted lines in Figure 1 no pieces are fed, neither on the table nor from the pile 7. This condition of the feeding apparatus is automatically brought about when the addressing machine has no line of type ready for printing. In the addressing machine the lines of type 80 are arranged close together in rows in 90 galleys or drawers 81 open below (Figure 3). In the pauses between printing operations, these drawers are intermittently shifted a distance equal to the thickness of one, two or three lines of type by means of a feed 95 mechanism that does not constitute part of this invention and is therefore not illustrated. Between the lines of type of two successive drawers there is a space 82 equal in size to the thickness of three lines of 100 type. If this space 82 registers with an opening 83 in the table, at the printing place, the piece lying over it will not be printed. But in order that this piece shall not be conveyed away unprinted, the operation of 105 the conveyer device is stopped by the device next to be described with reference to Figures 1 and 3.

Below two beams 84 constituting the track of the drawers 81 is arranged a two-armed 110 feeling lever 85 an upwardly directed tooth 86 which under the influence of a spring 87 is held in contact with the bottom of that line of type which arrives over it below the aperture 83 at the next feed movement of 115 the type. The end of the feeler lever 85 remote from the spring 87 is connected by a connecting rod 88 with a lever 90 that is fulcrumed at 89 and bears upwards against the periphery of a disk 92 from which a quadrant has been removed to form a recess as shown at 91. In the vertical plane parallel with and containing the axis of the shaft 93 of the disc 92 the lever 90 is cranked downwards and provided on its arm 94 with a 120 laterally projecting pin 95. Within reach of the latter is the hook of a catch 96 suspended at 98 on a draw rod 97. This rod is slidingly guided at its lower end by a pin 100 projecting into a longitudinal slot 99, and is pivoted 130

at its upper end to a lever 101 fast on the shaft 68 of the lever 69. The catch 96 has an arm 102 connected by a spring 103 with the draw rod 97. This spring 103 holds the 5 catch 96 in engagement with the pin 95 and a pin 104. This pin 104 is mounted on a cam 105 fast on the shaft 93 between the catch 96 and the disc 92.

If a line of type 80 is situated over the 10 tooth 86, the lever 85 cannot move the lever 90, 94 upwards when the recess 91 in the disc 92 rotating in the direction of its arrow arrives at the heel of the lever 90, 94. Consequently the pin 95 cannot engage with the 15 catch 96, the draw rod 97 remains in its upper end position, the lever 69 remains in its vertical position, the fingers 33 hold the switches 29 in the position shown in full lines in Figure 4, the cam 64, the rod 61, the 20 feed hooks 48 as well as the roller 85, the arms 77 and 78 and the member 79 remain in their lower positions, in which the pieces of paper are conveyed to the printing place and from there to a place where they are collected. If, however, there is no line of type 25 above the tooth 86, for example between two successive galleys 81, the lever 85 can move the lever 90, 94 upwards when the recess 91 arrives at the heel of the said lever 90. The 30 pin 95 engages with the catch 96 and pulls it and the rod 97 downwards, when the lever 90, 94 is forced down by the rear end of the recess 91 of the disc 92. The lever 69 is thereby moved out of its vertical position 35 shown in full lines in Figure 1 into the slanting position indicated by dotted lines, and thereby moves the switches 29 into the closed position and the feed members 48 and 79 upwards, so that the feed of the lay-on apparatus is stopped. As soon as the pin 104 40 strikes the catch 96, the latter is pushed away from the pin 95. The spring 71 which is stronger than the springs 32 acting together causes the levers 72 and 69 with the 45 fingers 33 and switches 29 connected therewith, as well as the feed hooks 48, member 79 and draw rod 97 with the catch 96 to return to their normal working positions.

In order that the piece of paper lying 50 partly on the table 1 and its ribs 1' shall remain stationary at a point suitable for its seizure by the feed hooks 48 and in order that there may be between that piece and the one at the printing place a space enabling the latter to be seized by the member 79, two wire bows or yokes 106 acting 55 as stops are arranged each on one of two levers 107 which rock about an axle 108 common to them both. The one lever 107 60 bears on the periphery of a disc 105 and is moved up and down by it.

Mounted on rearwardly directed arms 65 110 of the boxes 21 are rollers 109 which prevent the lifted piece of paper from moving forward with the points 14 when the levers

13 carrying the latter swing away from the pile 7. Obviously, adjustable sheet-metal side pieces, not shown, are preferably provided for guiding the pieces of paper at the 70 two sides.

The operation of the described laying-on apparatus used in connection with the addressing machine referred to is, briefly, as follows:—

The front piece of a pile 7 of papers 75 standing on edge on the plate 3, which piece bears against the stop 9 and the roller 38, is lifted over the stop 9 by the point-carrying levers 13 during their upward movement. The lifted piece of paper is 80 held against the pile 7 by the roller 38 until the lever 36 with said roller is moved away by means of the pin 40 on the lever 41 and the rod 39. The said piece of paper thus released drops down, and guided forward 85 by the stop 9, arrives in a slanting position on the forwardly moving upper lengths of the belts 44. These convey the piece to the stops 106 in the form of yokes that project up above the level of the table 1 and its 90 ribs 1'. The feed hooks 48 which have reached their end position (behind the piece of paper lying on the table), when the point-carrying levers 13 begin to move downwards, push the piece of paper to the 95 printing place, i. e., above the aperture, over the stop 106 which in the meantime have moved down under the table 1. During the next part of the cycle of operations the piece of paper is pushed away by the 100 member 79 from the printing place. Thus one piece is fed by the hooks 48 to the printing place and at the same time the previous piece is conveyed away by the member 79. This operation is repeated as often as lines 105 of type are ready in position for printing. But as soon as there is no such line of type 80 above the tooth 86 of the lever 85, the operation of the feeding apparatus is stopped as described above because the parts 110 13, 14, 48 and 79 are kept out of reach of the next piece of paper. This condition lasts as long as there is no line of type above the tooth 86 on the lever 85, but as soon as the next line arrives at this place the apparatus automatically begins to feed again. It will therefore be seen that there is no need for the operation of the apparatus to be stopped and restarted when printing stops, whereby a considerable amount of 115 time and power is saved. Preferably the speed of the apparatus is so selected that the duration of one swing of the arms or pendulums 51 which carry the feed hooks 48 and the member 79 at least approximately synchronizes with the oscillation of the arms 13. In this manner it is possible to operate the apparatus without excessive shaking and with a minimum expenditure of power.

I claim:

1. In a device for feeding folded matter to printing apparatus, the combination with a support for supporting a pile of folded matter edgewise, of movable arms carrying points adapted to be driven into the front piece of the pile, means for swinging said arms so as to drive the said points in their longitudinal direction into said front piece and then moving said arms upward and in a direction at right angles thereto away from said pile, thereby separating the pierced piece from the pile, conveyer means adapted to receive the piece after it is released by said points and convey it to the printing apparatus, and means operated by the printing apparatus for controlling the operation of the printing and conveying means.
2. In a device for feeding folded matter to printing apparatus, the combination with a support for supporting a pile of folded matter edgewise, of two levers each carrying a point disposed at right angles thereto adapted to be driven into the front piece in the pile, means for reciprocating said levers endwise and also in a direction at right angles thereto, means for preventing the reciprocation in the transverse direction whilst permitting it in the direction at right angles thereto, and a spring tending to rock said levers in the direction to drive said points into a piece of matter in the pile.
3. A device as specified in claim 1, comprising also a spring-controlled stop at the lower end of the said plate adapted to yieldingly engage the lower portion of the front piece of the edgewise supported pile.
4. In a device for feeding folded matter to printing apparatus, the combination of a table, a conveyer member arranged relative thereto so as to convey folded matter along the said table, a plate slanting downwards toward the said table, and adapted to support a pile of folded matter edgewise, an upwardly tapered yielding stop at the lower end of said plate for coacting with and arresting the bottom portion of the front piece of said pile, means comprising points directed toward the said pile, and adapted to be driven into the front piece thereof, means adapted to move said points in their longitudinal direction into the front piece and then move said points upwards and in a direction at right angles thereto, away from the pile, for separating the engaged front piece of the pile, and lifting it over said stop and finally allowing the said piece to drop onto the said conveyer member, and means actuated by the said printing apparatus for controlling the movement of the said points.
5. In a device for feeding folded matter to printing apparatus, the combination with a slanted plate adapted to support a pile of folded matter edgewise, of two levers each carrying a point directed at right angles thereto so as to be driven into the front piece of the said pile, means for reciprocating said levers endwise and in a direction at right angles thereto, an upwardly directed disengaging lever mounted to rock between the point-carrying levers, a roller carried by said disengaging lever at its end nearest said plate means operatively connected with the point-carrying levers for rocking the roller-carrying lever upwards away from said plate before the point-carrying levers arrive in their upper end position, and means operated by the said printing apparatus for controlling the operation of said levers.
6. In a device for feeding folded matter to printing apparatus, the combination of a table, two endless belts, one at each side thereof, having their upper lengths located slanting downwards from the rear end of the table towards the front above the level thereof, a support adapted to support a pile of folded matter edgewise at the rear end of the table and slanting downwards towards the same, two vertical levers each carrying a point directed at right angles thereto and adapted to be driven into the front piece of the pile, means for reciprocating said levers endwise and in a direction at right angles thereto, an upwardly directed disengaging lever mounted to rock vertically between the said point-carrying levers, a roller carried by said disengaging lever at its end nearest said support, and means operatively connected with the said point-carrying levers for rocking the said roller-carrying lever upwards away from said support and thereby releasing a lifted piece of folded matter and allowing the same to drop on to said belts prior to the said point-carrying levers arriving in their upper end position.
7. In a device for feeding folded matter to printing apparatus, the combination with a table having a printing place, of a support adapted to support a pile of folded matter edgewise at one end of the said table, conveyer belts arranged alongside the table from the support end thereof toward the printing apparatus, pivoted levers carrying points, means for reciprocating the same both vertically and horizontally to drive the points into the front piece of the folded matter thereby separating the folded matter piece by piece from said pile and delivering the same to said belts, a pendulum rod arranged to swing in a vertical plane between said belts in the direction of the length of said table, means operatively connected with said rod for pushing one piece of folded matter after another from said belts to said printing place, and means operatively connected with said rod for successively removing the pieces from the printing place, and means

operated by the said printing apparatus for controlling the said levers.

8. In a device for feeding folded matter to printing apparatus, the combination with 5 a table having a printing aperture, of a support adapted to support a pile of folded matter edgewise at one end of the table, conveyer belts arranged alongside the said table from the support end towards the printing 10 aperture, means comprising adjustable cams and point-carrying levers controlled by the latter, said levers being adapted to be reciprocated vertically and horizontally for removing folded matter by the said points 15 piece by piece from said pile and delivering the same to said belts, a pendulum arranged to swing in the direction of the length of said table, a pusher member operatively connected with said pendulum for pushing one 20 piece of folded matter after another from said belts to said aperture, a bowed member operatively connected to said pendulum for successively removing the pieces from the printing place, a control lever operatively 25 connected to said pusher member, said bowed member and said cams, a feeler lever arranged to coact with a line of type at said aperture, and mechanism controlled by said feeler lever and operatively connected with 30 said control lever for shifting the latter, when said aperture is not occupied by a line

of type and thereby arresting the feed of pieces of folded matter to said belts.

9. In a device for feeding folded matter to printing apparatus, the combination with 35 a table having a printing aperture, of a plate adapted to support a pile of folded matter edgewise at one end of the table, conveyer belts arranged parallel with the table from the plate end towards the printing place, 40 means comprising point-carrying levers reciprocated vertically and horizontally for removing folded matter piece by piece from the pile and delivering the same to said belts, feeding means for feeding one piece of folded matter after another from said belts to 45 said aperture, means operatively connected with the latter means for successively removing the pieces from the printing aperture, and stops movable vertically from under to over the level of the table and reversely located between said feeding means and said aperture and adapted to be moved downwards below the level of the table, 50 whilst a piece of folded matter is being fed 55 to said aperture.

In testimony whereof, I affix my signature in the presence of two witnesses.

JOHANN SCHEUNER.
